UNITED STATES PATENT OFFICE.

JAMES OSGOOD BRADLEY, OF MEMPHIS, TENNESSEE.

DESIGN FOR A SHELF-TRAY.

SPECIFICATION forming part of Design No. 27,354, dated July 13, 1897.

Application filed June 3, 1897. Serial No. 639,342. Term of patent 7 years.

To all whom it may concern:

Be it known that I, JAMES OSGOOD BRADLEY, a citizen of the United States, residing at Memphis, in the county of Shelby and State of Tennessee, have invented a certain new and useful Design for a Shelf-Tray; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to a certain new and useful design for shelf-trays, such as are designed for use upon shelves in stores and are adapted for use in storing goods in such manner as to permit of their being readily accessible.

My design is clearly illustrated in the accompanying drawings, which form a part of this specification, and in which—

Figure 1 is a perspective view of a shelf-tray embodying my design. Fig. 2 is a central longitudinal vertical section of the same.

Reference being had to the drawings, it will be observed that the tray embodying my de-

sign consists, essentially, of a substantially rectangular bottom plate, the said base-plate being formed upon an arc of a circle, as shown at A², this curved end portion being provided with a suitable handle B. At a point substantially one-third of the length of the tray, measuring from the curved end of the base-plate, is provided a vertical wall or partition C. The parallel sides D are of a height equal to the height of the end wall E of the tray for a distance of substantially one-half the length of the tray, measuring from the end wall E, and then the sides curve upward to the level of the upper edge of the wall C, and from this point the said side walls curve downward by a double curve as they approach the curved end of the base-plate.

What I claim to be new, and desire to secure by Letters Patent, is—

The design for a shelf-tray, substantially as herein shown and described.

In testimony whereof I affix my signature in presence of two witnesses.

JAMES OSGOOD BRADLEY.
